(57) **CLAIM**

The ornamental design for a racket string straightener, as shown and described.

DESCRIPTION

FIG. 1 is a perspective view of a racket string straightener in accordance with this invention;

FIG. 2 is a front elevational view of the racket string straightener of FIG. 1, the rear elevational view being a mirror image thereof;

FIG. 3 is a top plan view thereof;

FIG. 4 is a side elevational view thereof, the opposite side being a mirror image thereof;

FIG. 5 is a bottom plan view thereof;

FIG. 6 is a front elevational view of an alternate embodiment thereof; the rear elevational view is the same as FIG. 2; and, FIG. 7 is a front elevational view of another alternate embodiment of this invention, the rear elevational view being the same as FIG. 2.
